UNITED STATES PATENT OFFICE

SEBASTIAN ZIANI DE FERRANTI, OF HOLLINWOOD, ENGLAND, ASSIGNOR TO FERRANTI, LIMITED, OF HOLLINWOOD, ENGLAND

ELECTRIC RADIATOR FIRE

Application filed May 29, 1928, Serial No. 281,529, and in Great Britain June 9, 1927.

This invention relates to electric radiator fires and has for its object to provide improved constructions possessing efficient radiant heat utilization characteristics.

At present it is customary to heat a room or apartment in a house either by hot pipes which heat the air and so the room or by means of an open fire which throws out heat in all directions (up to the ceiling as well as on to the floor) apart from the heat lost up the chimney.

The present invention provides means for heating or keeping warm by direct radiation the people in the room, especially those sitting down.

According to the invention a fan-like beam is projected covering most of the room and of a depth sufficient to cover the bodies of sitting people and yet not rising high enough to burn their faces. People standing in the room only have their legs heated but as they are moving about they require less heat than those sitting still.

The necessary beam may be produced by a heater using as little as 2 kilowatt hours of energy per hour by methods of construction in accordance with the present invention and on account of its concentration is very intense and keeps a number of people thoroughly warm in a fair-sized room. What is not absorbed by the people in the room heats up the floor and walls to a small height which in their turn are in the best position for radiating their heat on to the people in the room.

Referring to the accompanying diagrammatic drawings:—

Figure 1 illustrates in side elevation one convenient construction in accordance with the present invention;

Figure 2 is a plan view partly broken thereof;

Figure 3a illustrates in cross-section a two-element heating unit.

Figure 3b shows a three-element heating unit in cross-section.

Figure 3c discloses in cross-section another form of heating unit of three elements.

In carrying the invention into effect in one convenient manner as illustrated in Fig-

ures 1 and 2 I provide a reflecting surface *a* of uniform parabolic vertical cross section and having divergent sides *b* *b*, the surface being carried upon a suitable stand *c* raising it some 6" from the ground. The foci of the parabolic sections lie in a straight line and as near as possible to this straight line I mount the radiating member. This radiating member comprises two separate units *d* *e* each of which is formed of two lengths of refractory high resistance material of bar section (about $1\frac{1}{4}$ "— $3\frac{1}{8}$ " in diameter). In the centre of the length of the reflector I provide a bracket *f* carrying an abutment member *g* of insulating and refractory material. At the two ends of the reflector, i. e., adjacent the divergent sides *b*, I provide flexible strips *h* of a metal bearing suitable sockets and serving to hold each of the refractory bars securely against the central refractory abutment before mentioned. The latter abutment is provided with two conducting studs with suitable socket ends with which the refractory bars contact. The sockets are preferably tipped with silver, silver alloy or are silver plated in order to provide a good electrical contact with the heater bar ends. Likewise the sockets in the flexible strips *h* are preferably silver plated. These flexible strips *h* pass through openings *j* in the sides of the reflector and at their ends remote from the heater are supported by and externally to the said reflector surface. Their length and radiating effect is sufficient to ensure that the supported ends (to which the electrical connections are made) do not attain an excessive temperature. The two heater bar ends are preferably disposed one behind the other in a horizontal plane and as closely together as possible, having regard to necessary electrical clearance, and a double pole switch *k* is provided by means of which one of the elements may be entirely disconnected at both ends from the supply circuit.

Conveniently flexible connecting leads (not shown) are provided for connection to an electric power supply source, the leads being partly housed in a beading *m* formed by rolling the edge of the reflector, thus at the same

time protecting them from mechanical damage, rendering them inconspicuous and stiffening the reflector.

The four flexible strips supporting the bar elements are preferably enclosed by end covers *n* suitably formed and attached externally to the sides of the reflector.

According to this construction heat is radiated mainly in a beam which is fan shaped

10 in a horizontal plane but which neither diverges nor converges appreciably in a substantially vertical plane and thus when the fire is placed in a room against one wall a beam of radiant heat is projected mainly in

15 a zone extending a few feet above the floor but sweeping practically the entire area of the floor. The heat generated is therefore utilized in the most efficient manner owing to this zone concentration.

20 It is necessary in order to be able to heat a definite zone economically that the source of heat shall lie as nearly as possible in the focus of the reflector. This is a simple matter when a single bar unit is employed.

25 Where two or three bars parallel to each other are employed they should be grouped as closely together as possible consistent with electrical clearance.

According to a modification instead of employing two heater units (each in two parts) formed of bars of circular cross section, bars of other cross section, for example two D-section bars disposed close together, Figure 3 (a), may be employed. Likewise it is not 35 essential to employ two units, since one, three or more may be employed in some cases.

30 A convenient arrangement when three are employed is to form each of sector shape in cross section as in Figure 3 (b) so that the 40 whole cross section occupied may be as compact as possible, thus yielding as far as possible a line source of radiant heat.

Another convenient construction of triple unit radiator member is to provide three 45 units which when erected in position occupy in cross section a circle divided into three parts by two vertical air spaces as in Figure 3 (c).

In all cases it is preferred that the unit 50 or units are formed as single bars, i. e. the central bracket *f* and abutment members *g* of Figure 2 are dispensed with.

Having now described my invention, what I claim as new and desire to secure by 55 Letters Patent is:—

1. An electric radiator fire embodying a reflector comprising a rear surface having a uniform parabolic vertical cross section symmetrical about the axis of the parabola 60 and two flat divergent sides disposed in vertical planes and joined to said rear surface, spring supports projecting with free clearance through slots in said reflector, and a resistance heating bar of small cross-sectional area disposed on the focal line of said rear

reflecting surface whereby a reflected heat beam is projected which diverges in horizontal planes but which does not diverge appreciably in vertical planes.

2. An electric radiator fire as claimed in 70 claim 1 wherein the said resistance heating unit comprises a group of elements, the exterior of the group conforming substantially to a circular contour of small diameter.

In testimony whereof I have signed my 75 name to this specification.

SEBASTIAN ZIANI DE FERRANTI.
